UNITED STATES PATENT OFFICE.

ARTHUR JULES FRANÇOIS JOSEPH COUSIN, OF SERAING, BELGIUM, ASSIGNOR TO SOCIÉTÉ ANONYME JOHN COCKERILL, OF SERAING, BELGIUM, A COMPANY.

CHECKER-WORK.

Application filed March 25, 1927, Serial No. 178,220, and in Belgium April 26, 1926.

My invention relates to improvements in the checker works of the apparatuses which are used for heating the air which is to be introduced in blast furnaces.

As it is well known, the checker works which are now in use and which are formed of bricks of little section do not possess the required stability, mostly after they have been working during a rather long time at a high temperature.

These well known refractory brickworks are generally composed of bricks which are provided with thin walls and which are piled up so as to form high columns. This construction has for its object to secure the greatest heating surface possible.

The columns thus formed however have no stability by themselves and are only held in place by the reciprocal support produced by their mutual contact. This support which is sufficient so long as the columns remain in a vertical position, has a tendency to fail when contractions occur under the action of the heat upon the refractory material, these contractions interrupting the contact between the columns which loose their verticality and tend to take an inclined position.

This tendency which takes place firstly in the upper parts of the checker works is gradually transmitted towards the lower parts and finally results in the overthrowing of all the regenerating system which does no more provide a free passage for the gas or air.

In order to obviate these disadvantages, it has been suggested to use numerous forms of special bricks provided with interlocking means such as projections, hooks and the like. These bricks are very expensive, require materials of first quality and are very difficult to be made. Moreover, they are of a great fragility and reduce the effective heating surface, the overthicknesses of material and other complications of form which are necessary to secure the interlocking being only obtained at the expense of the extension surface. My invention has for its purpose to obviate these disadvantages.

With this object in view it consists essentially in the special arrangements and combinations of parts hereinafter fully described and pointed out in the appended claims.

Referring to the annexed drawing:

Fig. 1 is a top view of a special arrange-

ment of bricks forming a layer of a checker work according to my invention the bricks having a square form.

Fig. 2 is a front elevation and Fig. 3 a side elevation corresponding to Fig. 1.

Fig. 4 is a view similar to Fig. 1, the layer being formed with circular bricks.

Figs. 5 and 6 are respectively a front elevation and a side elevation corresponding to Fig. 4.

The checker work forming the subject matter of my invention comprises a series of superposed layers of brickworks, one of which is indicated on the drawing. Each layer is formed of an equal number of rows of simple and double bricks which are arranged in alternate lines so as to form a combination of the following rows of bricks:

(1) One row 1—1 of simple hollow bricks α leaving free between them spaces or intervals b for the passage of the warm gases and each being provided with a circular opening c for the passage of the blast or reciprocally.

(2) One row 2—2 of double bricks d formed by the juxtaposition of two simple bricks connected to each other by a diagonal portion h of refractory material each double brick being placed in the direction of the line A—A.

(3) One row 3—3 of simple bricks α arranged similarly to the bricks of the first row 1—1 but displaced thereto so as to correspond to the spaces or intervals b between the bricks of the first row.

(4) One row 4—4 of double bricks d placed in the direction B—B at right angles to the line A—A.

Each double brick d of the rows 2—2 or 4—4 is in contact by the edges e with the next double brick in the same row and by the other edges f with the next simple bricks in the rows 1—1 or 3—3 so as to cooperate with the latter to the formation of the ducts g for the passage of the gases.

As shown on Figs. 1, 2, 3 the bricks generally possess a square section, but they may also receive any other suitable form such as a round (Fig. 4) or polygonal section.

When round bricks are used, the arrangement of the rows of bricks is the same, but the double bricks d are tangential to the next double brick and also to the simple bricks of the rows 1—1 and 3—3.

In order to avoid the sliding of the rows of bricks one upon another in the horizontal

direction, the height of the simple bricks may be different from that of the double bricks at least for the first under layer so that the difference of height secured in this 5 lower layer can be maintained in the several layers although using, for the upper layers bricks having the same height. In such conditions the several rows of simple and double bricks are placed at different levels in a same 10 layer as it will appear from Figs. 2 and 3 and Figs. 5 and 6 respectively.

Such a construction maintains the stability, the alternate rows of double bricks avoiding the overthrowing in two directions 15 at right angles to each other and producing by their contact a support for the lines of simple bricks.

The interposition of the rows of simple bricks has for its object to increase the heating surface without interfering with the stability. 20

The necessary and sufficient stability could be also obtained by using only double bricks but this stability would be obtained at the 25 expense of the heating surface, as it is the case when bricks of special forms are used.

The double bricks are obtained by the juxtaposition of two simple bricks, moulded simultaneously so as to be connected to each 30 other on a rather little portion h of their periphery.

In the checker works which must be submitted to a high temperature in their whole mass, the number of simple bricks must be 35 equal to that of the double bricks. In other

kind of regenerators and in the parts which must be submitted only to a moderate temperature (less than 1000° C. in the Cowper apparatus for example) the system herein-before described may be kept for the most 40 heated parts of the construction, the other parts being built only with simple bricks.

The price of the double bricks is very low as indeed bricks of this kind can be made by means of earths which are only a little aluminous and very cheap. They are moreover 45 very resisting and not adapted to be injured by handling. They are improvized with hooks, or other interlocking means even in the case of cylindrical bricks. 50

What I claim is:

1. In a checker work comprising a plurality of superposed layers of bricks, rows of simple bricks and rows of double bricks the 55 rows of simple bricks alternating with the rows of double bricks in each layer.

2. In a checker work comprising a plurality of superposed layers of bricks, rows of simple bricks and rows of double bricks, the bricks in the rows of simple bricks being placed at intervals from each other and being displaced relatively to each other in the successive rows and the bricks in the rows of double bricks being alternately arranged in directions at right angles to each other in the successive rows of double bricks. 60 65

In testimony whereof I have affixed my signature.

ARTHUR JULES FRANÇOIS JOSEPH COUSIN.
